UNITED STATES PATENT OFFICE.

WILLIAM D. SHURTZ, OF BALTIMORE, MARYLAND.

TEMPORARY ELASTIC HORSESHOE.

SPECIFICATION forming part of Letters Patent No. 359,897, dated March 22, 1887.

Application filed September 18, 1886. Serial No. 213,962. (No model.)

To all whom it may concern:

Be it known that I, WILLIAM D. SHURTZ, a citizen of the United States, residing at Baltimore, in the State of Maryland, have invented 5 certain new and useful Improvements in Horse-shoes; and I do hereby declare the following to be a full, clear, and exact description of the invention, such as will enable others skilled in the art to which it appertains to make and 10 use the same.

My invention relates to improvements in temporary elastic horseshoes wherein is provided a rubber shoe so constructed that it will be held securely and firmly to the horse's foot 15 by properly-placed projections integral with the said shoe, and with such openings as will afford proper ventilation and prevent the accumulation of gravel or dirt between the shoe and the foot. I accomplish this by a shoe 20 constructed in the manner illustrated in the accompanying drawings, in which—

Figure 1 is a vertical section through α of Fig. 2. Fig. 2 is a plan of the shoe. Fig. 3 is an end elevation.

Similar letters refer to similar parts throughout the several views.

The letter A designates the entire shoe with its sole or shoe proper, α ; the upper α' , and the strap α'' , made entirely of one piece of rubber.

The shoe A is provided with the opening α' for adjusting, and the heart-shaped opening α'' in the sole, which, with the opening α' in the rear of the shoe, affords a proper and sufficient ventilation, the bottom opening, α'' , at the same 30 time permitting the passage of any gravel or dirt which may be picked up, and preventing any accumulation which might be uncomfortable or injurious to the horse's foot.

The shoe is held on the horse's foot by being stretched over the hoof and held thereon by 40 the elasticity of the rubber, the upper α' serving to hold the toe, and the strap α'' , passing around the ankle, serving to keep the entire shoe in position. The strap α'' is provided with the enlarged part α''' , which fits closely into the 45 hollow of that part of the ankle, and the shoe is thereby held securely.

On the rear part of the sole α is the frog or raised part α'' , which fits closely into the hollow of the horse's hoof, and serves to hold the 50 sole rigidly in position in connection with the enlarged part α''' in the strap α'' .

I am aware that temporary horseshoes constructed of rubber or other elastic material have been heretofore used. Therefore, 55

What I claim, and desire to secure by United States Letters Patent, is—

1. A temporary horseshoe constructed of rubber or other elastic material, provided with the sole α , having the opening α'' , the raised portion α''' on the sole α , the upper α' , and the strap α'' , with its enlarged part α''' , substantially 60 as shown, and for the purpose set forth.

2. A temporary horseshoe constructed of rubber or other elastic material, provided with the sole α , having the opening α'' , the raised portion α''' on the sole α , the upper α' , and the strap α'' , for the purpose set forth. 65

In testimony whereof I affix my signature in presence of two witnesses.

WILLIAM D. SHURTZ.
